GUIDE FRAME FOR A ROTATING MORTISING TOOL

Frank S. Person, St. Paul, Minn.

Application October 19, 1953, Serial No. 386,754

1 Claim. (Cl. 144—27)

This invention relates to an improvement in guide frame for a rotating mortising tool and deals particularly with an apparatus for mortising hinge recesses which employs a portable drill.

Considerable difficulty is experienced in mortising hinges into doors and door frames. It is usual practice to cut into the wood along a predetermined outline with a chisel or other such tool and then to cut out the wood within the outline. This requires considerable skill, particularly in maintaining a proper depth throughout the recess. While devices have been provided for mortising into the wooden panel, such devices have been extremely costly. Furthermore, the wood is mortised through the use of a rotating bit which rotates on an axis at right angles to the plane of the surface being mortised. As a result the mortised aperture is provided with rounded corners which must either be cut away or which must be used in conjunction with hinges having rounded corners. This device also requires a gauge bar as long as the door which is awkward to carry about and to handle.

An object of the present invention resides in the provision of a hinge recess mortising tool which is inexpensive to construct and which is extremely effective in its operation. Virtually all carpenters are equipped with a small portable electric drill. By mounting this drill in a suitable frame and by equipping the drill with a suitable drill bit it is possible to effectively mortise the hinge recess at relatively low cost. My device is also useful in providing mortises for certain types of strike plates and other objects where the mortised recess adjoins an edge of the door or frame.

A feature of the present invention resides in the provision of a mortising tool which includes three main parts. The first of these parts is a frame which fits against the door or door frame in the location of the area to be mortised. The second main part includes a slideable carriage which slides within the supporting frame and moves toward and away from one end of the frame. The third main part includes a portable electric drill which in operation is secured to the carriage to move in conjunction therewith.

A feature of the present invention resides in the fact that the supporting frame and carriage are extremely simple in nature and can be very inexpensively produced. The carriage is equipped with fastening means such as U-bolts to clamp an electric drill to the carriage. Thus by inserting the electric drill on the carriage and tightening the two U-bolts, the apparatus is in readiness for operation.

A feature of the present invention resides in a means of easily adjusting the depth of recess. One side of the frame is equipped with an adjustable bracket which is adjustable relative to the supporting frame. By adjusting this single bracket the depth of cut of the mortising blade may be adjusted.

A feature of the present invention resides in the provision of a mortising tool in which the cutting mortising blade is of relatively small diameter. The blade is simi-

2

lar to a twist drill in most respects but is provided with an end of different design. The end of the drill is substantially flat so that when the inward movement of the drill is limited, the blade will only cut to a certain distance from the door edge and a sharply defined edge is produced.

A further feature of the present invention lies in the simplicity of adjustment of the apparatus. The length of the cut being formed and the positioning of the frame relative to the door frame or the door may be adjusted by means of screws or bolts. As a result no special tools are required for setting the apparatus to cut a mortising recess of the proper depth and size.

These and other objects and novel features of the invention will be more clearly and fully set forth in the following specification and claim.

In the drawings forming a part of the specification: Figure 1 is a side elevational view of the apparatus in position to work upon a vertical door or door frame.

Figure 2 is a cross sectional view through the apparatus, the position of the section being indicated by the line 2—2 of Figure 1.

Figure 3 is an end elevational view of the apparatus when set to make a mortising recess of maximum depth.

Figure 4 is a view similar to Figure 3 but showing the apparatus set to make a shallower recess.

Figure 5 is a detailed view of the adjusting bracket.

Figure 6 is an elevational view of large form of the mortising blade which is employed in the drill.

A mortising apparatus is best illustrated in Figures 1 and 2 of the drawings. Figure 1 shows a generally rectangular frame having parallel side drives 10 and 11 which are connected at one end by a cross member 12 and at the other end by a cross member 13. A cross member 14 is connected between the sides 10 and 11 at right angles to the cross member 12 and adjacent to this cross member.

The sides 10 and 11 are provided with parallel longitudinally extending grooves 15 which are perhaps most clearly illustrated in Figures 3 and 4 of the drawings. A carriage 16 in the form of a flat board or similar structure is provided with tongues 17 which engage into the grooves 15 and are slidably supported thereby. The carriage 16 is provided with a shallow recess 19 located centrally between its sides and intended to accommodate the upper surface of an electric drill 20. The shape of this recess 19 may vary to some extent depending upon the make of drill for which the carriage is built.

A U-bolt 23 encircles the round portion of the drill casing adjoining the chuck 22 thereof. The ends of the U-bolt 23 extend through the carriage 16. Nuts 24 on the ends of the U-bolt 23 act to clamp the round portion 21 of the drill 20 against the carriage 16.

The second U-bolt 25 encircles the body of the drill in spaced parallel relation to the U-bolt 23. The ends of the U-bolt 25 also extend through the carriage 16 and are held in place by clamping nuts 26. The U-bolts 23 and 25 are so arranged that the axis of the drill extends parallel to the axis of movement of the carriage 16.

A spring 27 is anchored at one end at 29 to the carriage 16 and is anchored at the other end at 30 to the cross member 12 at one end of the frame. This spring 27 acts to draw the carriage 16 into one extreme position as illustrated in Figure 2 of the drawings.

The cross member 13 is provided at its center with a knob or handle 31 by means of which the frame may be held in proper relation to the door frame or to the door. This knob 31 permits the frame to be held in proper relation to the various door surfaces.

As best shown in Figures 2 and 5 of the drawings the frame sides 10 and 11 are notched at 32 to provide relatively short projections 33 which terminate in shoulders 34. The sides extend somewhat beyond the shoul-

ders 34 as indicated at 35 so as to support the cross member 13 forwardly of the shoulders 34. One surface of the cross member 13 may be cut away or bevelled at 36 so that the portion being mortised may be more easily viewed and so that the chips being formed may more easily be discharged.

Wood screws 37 are provided projecting forwardly each of the shoulders 34 as best illustrated in Figure 5 of the drawings. These screws 37 may be adjusted to provide a proper spacing between the shoulders 34 and the edge of the door or door frame and also to adjust for any variations in the edge of the door or frame. By screwing one or both of these screws inwardly the corresponding shoulder or shoulders 34 are moved closer to the door edge and obviously the two screws must be the same distance from the shoulders if the drill is to extend at right angles to the door edge if the door edge is square.

As best shown in Figures 1 and 2 of the drawings an adjustment screw 39 extends into the carriage 16 at one end thereof and the headed end of this screw extends through an aperture 40 in the cross member 12. This screw 39 may be threaded inwardly or outwardly in order to determine the extent of movement of the carriage 16. Thus by operation of this screw 39 the cutting drill or blade may be adjusted to provide the proper width of mortise.

One surface of the projecting end portion of a side member 11 is provided with a surface 41 which is resistant to slipping. For example, a strip of abrasive cloth may be adhered to this surface which engages the surface of the door or door frame. This assists in preventing the slipping of the frame relative to the part mortised during the operation of the apparatus.

As best shown in Figures 1 and 5 of the drawings an adjustment bracket 42 is secured to the side edge of the frame side 10 by means of clamping bolt 43 or other suitable means. The clamping bolts 43 extend through parallel slots 44 and the bracket 42 and permit movement of the bracket plate in a direction toward or away from the surface of member being mortised. Figure 3 shows the bracket plate 42 completely retracted and in this case the cutting tool will cut a mortise of maximum depth. By adjusting the plate 42 toward the surface being mortised as indicated in Figure 4 of the drawings the entire frame is tilted to some extent, thereby decreasing the depth of the mortise.

The cutting drill, or blade, is best indicated at 45 in Figure 6 of the drawings. As indicated in this drawing the blade is somewhat similar to a twist drill and for the most part the end 46 of the drill is flat or on a plane normal to the axis of the drill. However, opposite edges of the drill have short projecting cutting edges which act to cut into the wood and hold the drill on a true course.

The operation of the apparatus is believed obvious from the foregoing description. The drill 20 is first mounted upon the carriage 16 and the cutting blade 45 is properly supported in the drill 20. The surface of the door and door frame to be mortised is laid out by drawing a line about the area to be mortised. A frame of the apparatus is next held against the surface to be mortised and the bracket 42 is adjusted to provide the

desired depth of cut. While holding the projecting ends 35 of the frame side members 10 and 11 slightly spaced from the surface to be mortised, the carriage 16 is moved forwardly to its extremity and the screw 39 is adjusted so as to limit the cut to the proper length. Alternatively the length of cut into the door may be measured and the screw 39 moved until the head of the screw is a distance away from the cross member 12 equal to the depth of cut.

10 The frame is next held against the member to be mortised with the drill even with an edge of the cut to be mortised. The carriage is then reciprocated to form a cut into the door or frame surface. The frame is then moved along the edge of the door a short distance and 15 another cut made. This operation is continued until the entire area has been mortised. By moving the cutting blade while in projected position throughout the length of the mortised cut, the short humps or ridges between the individual cuts may be easily cut down. Alternatively these cuts may be smoothed down by a chisel or other such cutting tool.

In accordance with the patent statutes I have described the principles of construction and operation of my mortising tool and while I have endeavored to set forth the 25 best embodiment thereof I desire to have it understood that obvious changes may be made within the scope of the following claim without departing from the spirit of my invention.

I claim:

30 A mortising tool for use with a power drill, the tool including a generally rectangular frame including a pair of spaced parallel sides connected at their ends by cross connecting members, the sides having guide grooves extending longitudinally thereof adjacent one longitudinal edge thereof, a reciprocatory platform slidably supported in said guide grooves, drill encircling means on said platform designed to attach the power drill thereto, work engaging notches in said sides at one end thereof and in said one longitudinal edge of each, said notches 35 each providing two right angularly arranged stop shoulders, one shoulder of which extends parallel to said guide grooves, said one shoulder of each of said notches being on a plane substantially tangent to the rotatable cutting portion of the power drill on the side thereof 40 most remote from said one longitudinal edge of said sides, adjustable means for selectively spacing either one of the right angularly arranged stop shoulders from the work piece and adjustable means to limit the sliding movement of said reciprocatory platform, said cross member connecting said notched ends of said sides being located on the other longitudinal edges of said sides.
